WILLIS H. CARRIER, OF BUFFALO, NEW YORK, AND EDWARD W. COMFORT, OF CHICAGO, ILLINOIS, ASSIGNEES TO BUFFALO FORGE COMPANY, OF BUFFALO, NEW YORK.

THERMOSTATIC REGULATING DEVICE.

13,947.

Specification of Reissued Letters Patent. Reissued July 20, 1915.

Original No. 929,655, dated August 3, 1909, Serial No. 455,208. Application for reissue filed August 3, 1911. Serial No. 642,172.

To all whom it may concern:

Be it known that we, WILLIS H. CARRIER, a citizen of the United States, residing at Buffalo, in the county of Erie and State of New York, and EDWARD W. COMFORT, a citizen of the United States, residing at Chicago, in the county of Cook and State of Illinois, have invented a new and useful Improvement in Thermostatic Regulating Devices, of which the following is a specification.

This invention relates to thermostatic instruments which are influenced by the temperature and hygrometric conditions of the surrounding atmosphere and are primarily utilized for regulating the humidity of the air. An instrument of this sort is disclosed in patent No. 896,690, granted August 18, 1908, to W. H. Carrier, assignor to Buffalo Forge Company, which comprises two expansible elements, one affected by the actual or "dry bulb" temperature of the surrounding air, and the other affected by the lower "wet bulb" temperature of the air produced by evaporating moisture around this element. As the evaporation of the moisture is more or less rapid, depending upon the hygrometric condition of the air, it follows that the "wet bulb" temperature of the air rises or falls relative to the "dry bulb" temperature in proportion as the air is more or less humid. Consequently the relative expansion or contraction of the two elements is dependent upon the relation existing between the temperature and the humidity of the air affecting them, and the position of a device operated by the conjoint differential action of these elements can accordingly be used, through suitable instrumentalities, for regulating the humidity of the air. The changes in the dry and wet bulb temperatures of the air which take place while the percentage of humidity remains constant, bear a practically fixed relation or ratio to each other within ordinary ranges of temperature, but the ratios differ for different percentages of humidity. Likewise, the ratio of changes in the dry and wet bulb temperatures of the air remains practically constant for the same absolute humidity, but differs for different absolute humidities. In said patented device, expansible elements having different coefficients of expansion are used and means are provided for changing

the ratio of expansion or contraction of the two elements to correspond to different ratios existing between the changes in the wet and dry bulb temperatures of the air under different conditions of humidity, so that by different adjustments of the device it will maintain different desired hygrometric conditions notwithstanding wide fluctuations in the temperature of the air.

One object of the present invention is to produce a reliable and accurate instrument of this character which is of simple and practical construction and can be readily adjusted to secure different desired hygrometric conditions, but in which expansible elements can be employed having the same or unchangeable coefficients of expansion. This is accomplished by providing two expansible elements, preferably alike, termed, for convenience, the "dry" and the "wet" elements, which are affected respectively by the dry and wet bulb temperatures of the air and operate the regulating device or valve through a lever mechanism by which said elements act with different leverages on the regulating device, and which lever mechanism is preferably adjustable to give different ratios of leverage between said elements, depending upon the desired result to be obtained.

The changes in dimensions of the thermostat elements produced by ordinary temperature fluctuations are, in practice, very small, and ordinarily complicated mechanism operated by the expansible elements is required for effecting the humidity regulation.

Another object of this invention is to produce an instrument of small size, and compact and durable construction, which will operate in response to these small changes in the expansible elements and will be efficient and reliable for humidity regulation.

In the accompanying drawings, consisting of two sheets: Figure 1 is a front elevation, partly in section, of a regulating instrument embodying the invention. Fig. 2 is a sectional elevation thereof in line 2-2, Fig. 1. Fig. 3 is an end elevation thereof. Fig. 4 is a sectional plan, on an enlarged scale, of the regulating valve.

Like letters of reference refer to like parts in the several figures.

A and B represent respectively the so-

called "dry" and "wet" expansible elements, which preferably consist of similar tubes of ebonite, or pieces of other suitable material having a high coefficient of expansion, and C represents a regulating device or lever. The dry and wet bulb elements A and B, as stated, are affected respectively by the actual, or dry bulb, and wet bulb temperatures of the air, provision being made for evaporating moisture around the wet element, and the two elements operate conjointly on the regulating device through an adjustable lever mechanism.

The expansible elements can be arranged and connected in different ways so that one will be thus affected by the wet bulb temperature of the air, and to allow for changing the ratio of their leverages on the regulating device. In the construction shown in the drawings, the dry element A is pivoted at one end to a post d projecting from a base or support D and is provided at its free end with a knife edge e which bears on a lever E. The element A can be swung on its pivot post d to cause its knife edge to bear on the lever at different distances from the lever fulcrum, and it is held, when adjusted, by a binding nut d' screwed on the pivot post d. The lever E has a knife edge engagement f with a second lever F which carries an adjusting screw G having a pointed end bearing against one end of the wet element B. The wet element B is provided at its other end with a reduced or pointed part bearing against the regulating device or lever C. The levers C, E and F are fulcrumed to posts projecting from the base, preferably by thin flat springs c', e' and f', respectively, which are fixed to the levers and posts. These fulcrum springs hold the levers in place and prevent looseness in the joints and lost motion between the parts, and the spring c' for the regulating lever C tends to move said lever toward and hold it against the end of the wet element B. The regulating device or lever will remain stationary or be moved in one or the other direction, depending upon the relative changes in length of the two expansible elements caused by changes in the temperatures affecting them, and the relative leverages which they exert on the regulating device.

The free end of the regulating lever C acts as a valve to control a bleeder or escape orifice h, Fig. 4, in a branch h' of a pipe H which supplies compressed air to the actuating diaphragm or motor of the apparatus (not shown) which regulates the humidity of the air. A restricting valve h² is provided in the air pipe H which permits only a very small quantity of air to pass to the regulating motor. If the bleeder orifice is closed by the regulating device C the air passing the restricting valve to the motor will operate the motor to move the part ac-

tuated thereby in one direction, whereas if the regulating device C is moved to open the bleeder orifice the air will escape from the diaphragm through the orifice faster than it can pass the restricting valve to the motor, thus permitting the motor to effect an opposite movement of the part actuated thereby. Thus the regulating device C by opening and closing the bleeder orifice h acts, through the humidity regulating apparatus, to effect a change in the humidity of the air. Very little force is required to operate the regulating device C and the movement thereof necessary for effecting the regulation is so small that the instrument regulates accurately and responsively to slight fluctuations in temperature and humidity. The described means whereby the movement of the regulating lever C effects the regulation are therefore desirable, but the invention is not restricted to these means and other instrumentalities governed by the movement of the lever C, or other part similarly actuated, can be employed for effecting the regulation.

The means shown for subjecting the wet element B to the wet bulb temperature of the air consists of a wick I of absorbent material which surrounds the wet element and is kept wet by dipping into a water receptacle i to which water is fed from the base D, which is hollow and forms a large water reservoir. A water supply pipe K connects with the reservoir above a partition which divides the reservoir into two chambers connecting through a hole k in the partition. A valve k' on a push rod k² extending through the top of the base controls the hole k. A spring k³ normally holds the valve k' off of its seat and holds a second valve k⁴ on the push rod against the inner end of an air vent passage k⁵ in the top of the reservoir. To fill the reservoir the rod k² is pushed downwardly to seat the valve k' and open the air vent k⁵, and the cock of the supply pipe K is then turned to admit water to the reservoir. When the reservoir is filled the push rod is released, when the reservoir will automatically replenish the water taken from the well by the wick I. Air is caused to circulate past the wet element B under a shield L partially inclosing the element and through a passage l in the base D to evaporate the moisture from the wick, by an aspirator l' which is located in said passage l. The shield L is preferably hinged to the base so that it can be turned back out of the way to permit the wick to be put in place. Any other suitable means can be employed for causing the temperature of the wet element to correspond to the wet bulb temperature of the air.

The operation of the instrument is as follows: Under conditions of saturation the dry and wet bulb temperatures of the air

are the same and any change in the actual temperature is followed by a like change in the wet bulb temperature, which results in the same change in the length of both of 5 expandible elements A and B. To maintain a saturated condition therefore it is necessary for the two elements to have an equal but opposite or compensating effect on the regulating device C, and the dry element A 10 must be adjusted to bear on the lever E at the point marked 100 per cent., when the ratio of the leverages of the two elements will be equal. Changes in the dry bulb temperature, when the humidity is less than 100 15 per cent., are accompanied by changes of different degree in the wet bulb temperature, but, as before stated, the changes in the dry and wet bulb temperatures bear a definite, practically constant ratio to each other 20 for any given percentage of humidity. For example, with a humidity of 50 per cent. a change of 10° in the dry bulb temperature will be accompanied by a change of 8½° in the wet bulb temperature. To maintain this 25 humidity, therefore, the dry element is set to bear on the lever E at the point marked 50 per cent., when the ratio of the leverages of the dry and wet elements will be as 10 to 8½, with the result that a 10 per cent. 30 change in the length of the dry element will offset or compensate for the effect on the regulating device C of an 8½ per cent. change in the wet element. In like manner, the proper ratios of leverages for other desired 35 percentages of humidity are secured by adjusting the dry element to the points on the lever E indicating such humidities. The instrument can also be adjusted to maintain a desired absolute humidity by setting the 40 dry element so that the ratio of the leverages of the two elements corresponds to the ratio of changes in the dry and wet bulb temperatures which exists with such absolute humidity. The lever F is marked 30° D. P., 40° 45 D. P., &c., to indicate the points at which the dry element should be set in order to maintain these respective dew points and the corresponding absolute humidities. Likewise, other desired conditions of humidity 50 could be secured by adjustments which would give the required lever ratios between the two expandible elements.

The described adjustment of the dry element on the lever E merely gives the required ratio of leverages to compensate for the temperature fluctuations. Besides this adjustment, the screw G is adjusted, as indicated by marks on its enlarged head, to properly set the regulating lever C to secure 55 the necessary difference between the wet and dry bulb temperatures for a desired humidity condition.

The wet bulb element B is preferably provided with a spring pressed block g for the 60 screw G to bear against, so as to give the

screw a yieldable bearing and thus avoid possible injury to the instrument.

While the instrument is made adjustable as explained, for changing the ratio of leverages with which the expandible elements 70 operate on the regulating device to adapt the instrument for securing different desired conditions of humidity, the invention is not necessarily limited to the use of an adjustable lever mechanism, because the instrument 75 will maintain a fixed condition of humidity if the expandible elements operate with an appropriate ratio of leverages on the regulating device.

We claim as our invention:

1. The combination of two expandible elements which are separately influenced by the dry and wet bulb temperatures of the air, a device which is adapted to be operated by the conjoint action of said expandible elements, and mechanism through which said expandible elements operate with relatively different leverages on said device, substantially as set forth.

2. The combination of two expandible elements which have corresponding coefficients of expansion and are separately influenced by the dry and wet bulb temperatures of the air, a humidity regulating device which is adapted to be operated by the conjoint action of said expandible elements, and lever mechanism through which said expandible elements operate with relatively different leverages on said regulating device, substantially as set forth.

3. The combination of two expandible elements which are separately influenced by the dry and wet bulb temperatures of the air, a device which is adapted to be operated by the conjoint action of said expandible elements, and mechanisms through which one of said elements may be caused to operate on said device with a different leverage from the other element, substantially as set forth.

4. The combination of two expandible elements which are separately influenced by the dry and wet bulb temperatures of the air, a device which is adapted to be operated by the conjoint action of said expandible elements, and motion-transmitting means which are adjustable to give different ratios of leverage between said expandible elements and said device, substantially as set forth.

5. The combination of two expandible elements which are separately influenced by the dry and wet bulb temperatures of the air, a device which is adapted to be operated by the conjoint action of said expandible elements and an adjustable lever mechanism by which the motion of said device produced by said expandible elements is regulated, substantially as set forth.

6. The combination of two expandible elements which are separately influenced by the dry and wet bulb temperatures of the

- air, a device which is adapted to be operated by the conjoint action of said expansible elements and is in operative connection with one of them, and lever mechanism between 5 said expansible elements, which mechanism is adjustable whereby said elements have an equal but opposite effect on said device under different atmospheric conditions, substantially as set forth.
- 10 7. The combination of two expansible elements, one of which is affected by the temperature of the air, means for evaporating moisture in the vicinity of the other element, a device which is adapted to be operated by 15 the conjoint action of said expansible elements, and motion-transmitting means which are adjustable to give different ratios of leverage between said expansible elements and said device, substantially as set forth.
- 20 8. The combination of two expansible elements which have the same coefficient of expansion and are separately influenced by the dry and wet bulb temperatures of the air, a device which is adapted to be operated by 25 the conjoint action of said expansible elements, and motion-transmitting means which are adjustable to give different ratios of leverage between said expansible elements and said device, substantially as set forth.
- 30 9. The combination of two expansible elements which have the same coefficient of expansion and are separately influenced by the dry and wet bulb temperatures of the air, a device which is adapted to be operated 35 by the conjoint action of said expansible elements, and a lever mechanism through which said expansible elements operate said device and which is adjustable for varying the action of said device, substantially as set forth.
- 40 10. The combination of expansible elements which are separately influenced by different temperatures, a regulating device which is adapted to be operated by the conjoint action of said expansible elements and is in operative connection with one of them, and lever mechanism between said expansible elements, which mechanism is adjustable whereby said elements have an equal 45 but opposite effect on said regulating device under relatively different temperature conditions, substantially as set forth.
- 50 11. The combination of two expansible elements which are separately influenced by

the dry and wet bulb temperatures of the 55 air, a device which is adapted to be operated by the conjoint action of said expansible elements and is in operative connection with one of them, and lever mechanism between said expansible elements, one of said elements having an adjustable connection with 60 said lever mechanism, substantially as set forth.

12. The combination of two expansible elements which are separately influenced by the 65 dry and wet bulb temperatures of the air, a regulating device which is adapted to be operated by the conjoint action of said expansible elements and is in operative connection with one of them, lever mechanism between 70 said expansible elements, which mechanism is adjustable, and means for adjusting the position of said regulating device, substantially as set forth.

13. The combination of two expansible elements which are separately influenced by the dry and wet bulb temperatures of the air, a device which is adapted to be operated by the conjoint action of said expansible elements and is in operative connection with 75 one of them, levers having an operative connection with each other, an adjustable connection between one of said expansible elements and one lever, and an adjustable connection between the other expansible element and another lever, substantially as set forth.

14. The combination of two expansible elements which are separately influenced by the dry and wet bulb temperatures of the 90 air, a regulating device in connection with one of said expansible elements, and lever mechanism between said elements having an adjustable connection with said other expansible element, substantially as set forth. 95
